COMBINED GAME DEVICE AND SAVINGS BANK

Elaine G. Vigan, 1932 Weepah Way,
Hollywood, Calif. 90010

Filed July 19, 1971, Ser. No. 164,188

Term of patent 14 years

Int. Cl. D21—01

U.S. Cl. D34—11

FIG. 1.

FIG. 2.

FIG. 3.

FIG. 1 is a perspective view of a combined game device and savings bank embodying my new design;

FIG. 2 is an end elevational view, and

FIG. 3 is a side elevational view illustrating the side opposite to that in FIG. 1.

I claim:

The ornamental design for a combined game device and savings bank, as shown.
